(Cl. D4—3)

Fig. 1.

Fig. 2.

To all whom it may concern:

Be it known that we, Charles L. Casey, a citizen of the United States and a resident of Riverside, in the county of Cook and State of Illinois, and Raymond G. Doell, a citizen of the United States and a resident of Elk Grove, in the county of Cook and State of Illinois, have invented a new, original, and ornamental Design for a Holder for a Roll of Paper, of which the following is a specification, reference being had to the accompanying drawing, forming part thereof.

Figure 1 is a perspective view of a holder for a roll of paper embodying our new design, the view being taken from one end of the holder.

Figure 2 is a similar perspective view taken from the opposite end of the holder.

We claim:

The ornamental design for a holder for a roll of paper, substantially as shown.
